OIL OR GASOLINE BARREL LOCK

Filed July 7, 1932

UNITED STATES PATENT OFFICE

1,938,886

OIL OR GASOLINE BARREL LOCK

William Onus York, Provost, Alberta, and Albert Ostgaard, Cadogan, Alberta, Canada

Application July 7, 1932. Serial No. 621,190

4 Claims. (Cl. 70—124)

The invention relates to improvements in oil or gasoline barrel locks and an object of the invention is to provide a device which can be readily applied on existing barrels to positively prevent an unauthorized person from obtaining oil or gasoline from the barrel and which is arranged such that one with a proper key can easily and quickly withdraw oil or gasoline from the barrel.

10 A further object is to construct the device in a simple, durable and inexpensive manner and so that it can be readily adjusted to accommodate barrel heads of varying diameter and further to arrange the parts so that when the faucet or draw off cock has been screwed into place, it cannot be unscrewed or removed.

A further object is to construct the device so that the barrel can be filled with oil in the usual manner by unlocking a closure cap or 20 cover and then removing the underlying screw plug and which is arranged also that the draw off faucet cannot be opened until the closure cap aforesaid has been opened and the screw plug released.

25 With the above more important and other minor objects in view which will become more apparent as the description proceeds, the invention consists essentially in the arrangement and construction of parts hereinafter more particularly described, reference being had to the accompanying drawing, in which:—

Fig. 1 is a vertical sectional view longitudinally and centrally through the device applied on a barrel.

35 Fig. 2 is a face view of the device and part of the barrel.

Figure 3 is a vertical sectional view at 3—3 Figure 1.

Fig. 4 is a perspective view of the tap receiving 40 collar.

Fig. 5 is a perspective view of the tap or faucet and lever.

In the drawing like characters of reference indicate corresponding parts in the several figures.

Oil and gasoline receiving barrels as now used are made from sheet metal and have one head 1 thereof provided with two diametrically opposing screw threaded openings 2 and 3 positioned somewhat in from the side of the barrel and both adapted to receive screw plugs for shipping purposes, the one hole 2 being considerably larger than the other and being used for filling purposes in some cases or for receiving an oil pump in others. Where an oil pump

is used, the hole 3 is closed by a plug but where an oil pump is not used, the hole 3 is provided with a faucet or draw off tap.

Our invention is particularly adapted for use where the barrel is placed in a horizontal position and a draw off tap or faucet 4 of the well known type is screwed into the hole 3 and the hole 2 is used for filling purposes and is normally closed by a plug 5 and such device is designed to prevent unauthorized withdrawal of gasoline or oil from the barrel.

The device comprises the parts now described in detail. A lower head 6 is provided and said head comprises mating front and rear plates 7 and 8 spaced apart by a marginal wall 9 and 70 suitably secured one to the other by bolts or rivets 10. The lower part of the head is supplied with a pair of circular openings 11 which receive rotatably the ends of a collar 12, the collar being supplied between the plates with a continuous flange 13 which prevents removal of the collar. The collar is provided with a hexagonal opening 14 adapted to receive the customary hexagonal enlargement 15 of the faucet and it is also supplied with a circular opening 16 adapted to receive freely the screw threaded end of the faucet, the arrangement being such that when the faucet is screwed into the barrel, the enlargement 15 turns the collar and the head 9 is firmly held against withdrawal by the enlargement 15 of the faucet.

When the faucet is being screwed into place, the collar rotates freely but it is prevented from rotation in the opposite direction by a spring pressed dog 17 pivotally mounted between the 80 plates and engageable with the flange and adapted to enter a notch 18 provided in the flange.

An extending bar 19 passes slidably between the plates and has the entered end lengthwise slotted at 20 and the slot containing an elongated 95 locking tongue 21 and the tongue supplied with a slot 22. The plates 7 and 8 are fitted with opposing transverse slots 23 and 24 which are adapted to receive a part later described to be locked by the tongue. A bolt 25 connects the plates 100 and passes through the slot 22 of the tongue and guides the bar in its end shifting movement.

An upper head 26 is provided which head is supplied with an extending shank 27 provided with a lengthwise extending passage 28 which receives slidably the adjoining end of the bar and the shank is fitted with a series of holes 30, one or other of which receives a screw 31, the screw being adapted to screw into one or other of a number of similar spaced screw threaded 110

holes 32 provided in the bar. The upper end of the head is provided with an interior cavity 33, the back wall of which is slotted as indicated at 34 and this slot is adapted to overlie the large 5 opening 2 of the barrel head. The plug 5 previously mentioned is screw threaded through the slot 34 into the opening 2 and it will be observed that the hexagonal head of the plug jams the back wall of the latter head against the barrel 10 head when the said plug is tightly screwed up and by so doing, prevents shifting movement of the head 26 in respect to the barrel head.

A cap or gate 35 is hinged to the head 26, and is supplied with an interior cavity so that ample 15 clearance will be provided for the plug 5 when the gate is closed. The gate is supplied with a slot 36 adapted to receive a staple 37 permanently fastened to the upper end of the shank,

A locking lever 38 is pivotally attached to the 20 upper end of the valve spindle of the faucet or tap and this lever carries a staple 39 adapted to enter the slots 23 and 24 when the lever is in the locked position.

By adjusting the screw 31, one can set the 25 device so that it will fit barrel heads of varying diameter and it will be here understood that the adjustment is made so that when the faucet is screwed through the lower head into the opening 3 of the barrel, the opening 34 in 30 the upper head will overlie the opening 2 of the barrel head.

Having adjusted the device according to the requirements of the openings 2 and 3, one screws the threaded end of the faucet into the opening 35 3 of the barrel through the lower head, the collar at such time turning and it is here to be remembered that the enlargement 15 of the faucet fastens the lower head of the device to the barrel head and that any unscrewing of the 40 faucet is subsequently prevented by the dog entering the notch. The faucet is locked in its closed position by passing the staple 39 into the slots 23 and 24 and then lifting the bar 19 to pass the tongue through the staple which prevents the subsequent movement of the locking 45 lever and accordingly effects the locking of the faucet in its closed position.

After the bar is raised to lock the lever by the tongue, one tightens up the plug 5 by a suitable 50 tool to cause the head thereof to effectively jam the back wall of the upper head against the barrel head and in so doing effectively fasten the upper head to the barrel. This being done, the cover or gate is closed and locked in its closed 55 position by a padlock 40 passed through the upper staple.

Once the padlock has been applied, it will be 60 obviously impossible for an unauthorized person to draw oil or gasoline from the barrel for the reason that the plug 5 cannot be reached unless the gate is open and such plug by its jamming action prevents the shifting of the bar and the consequent release of the tongue from the lower 65 staple.

An authorized person, however, that is, one 70 having the key to the padlock, can easily draw gasoline or oil from the barrel as he simply has to undo the padlock, open the gate, screw back the plug 5, to permit the top head and bar to drop and when this has occurred, the tongue has 75 withdrawn from the lower staple and the locking lever is free and can be turned in the proper direction to rotate the faucet valve stem to open position,

While we have entered into a detailed description of the various parts, it will be understood that they could be structurally modified without departing from the spirit of the invention as set forth in the accompanying claims.

80

What we claim as our invention is:—

1. A barrel lock comprising a pair of heads, one of which is provided with a faucet receiving opening and the other of which is provided with a plug receiving opening, a closure cap for covering the plug receiving opening, a releasable lock for locking the cap closed, a bar having one end secured to the latter head and the other end slidably received within the former head and provided with a concealed locking tongue approachable through suitable opposing transverse slots provided in such head and a faucet locking member entering the slots and engageable with the tongue in the end shifting movement of the bar.

85

2. A barrel lock comprising a lower head having a faucet receiving opening passing therethrough, an upper head having a plug receiving opening therein, a closure cap hingedly secured to the upper head and adapted to cover the opening therein in the closed position of the cap, means for locking the cap closed, a bar secured to the upper head and slidably received within the lower head and provided within the lower head with a concealed locking tongue approached through opposing transverse openings provided in the lower head and a faucet locking member entering the slots and engageable with the tongue in the end shifting movement of the bar.

90

3. A barrel lock comprising a lower head; a non-removable collar rotatably mounted in one end of the head and provided with a central faucet receiving aperture, means preventing rotation of the collar in one direction; an upper head having a plug receiving opening therein, a closure cap hinged to the upper head and adapted to cover the opening in the closed position of the cap, a releasable lock for locking the cap closed, a bar having one end secured to the upper head and the other end slidably received within the lower head and provided with a concealed locking tongue; said locking tongue being approachable through opposing transverse slots provided in the lower head and a faucet locking member entering the slots and engageable with the tongue in the end shifting movement of the bar.

95

4. A barrel lock comprising a lower head; a non-removable collar rotatably mounted in one end of the head and provided with a central faucet receiving aperture, means preventing rotation of the collar in one direction, an upper head having a plug receiving opening therein; a closure cap hinged to the upper head and adapted to cover the opening in the closed position of the cap, a releasable lock for locking the cap closed; a bar having one end adjustably secured to the upper head and the other end slidably received within the lower head and provided with a concealed locking tongue; said locking tongue being approachable through opposing transverse slots provided in the lower head and a faucet locking member entering the slots and engageable with the tongue in the end shifting movement of the bar.
